UNITED STATES PATENT OFFICE.

JOHN H. BURKHOLDER, OF ASHLAND, OHIO.

DOOR-HANGER.

No. 861,083.

Specification of Letters Patent.

Patented July 23, 1907.

Application filed December 13, 1906. Serial No. 347,709.

To all whom it may concern:

Be it known that JOHN H. BURKHOLDER, a citizen of the United States, residing at Ashland, in the county of Ashland and State of Ohio, has invented new and 5 useful Improvements in Door-Hangers, of which the following is a specification.

This invention relates to door hangers, and one of the principal objects of the same is to provide efficient and reliable means for preventing the hanger from 10 becoming disengaged from the track when the door is blown outward by the wind.

Another object is to provide simple and reliable means for supporting the tubular track for the hanger. These and other objects are attained by means of 15 the construction illustrated in the accompanying drawings, in which,—

Figure 1 is a front elevation of a door hanger embodying my improvements; and Fig. 2 is a side elevation of the same, the tubular track being shown in 20 section on the plane indicated by the line 2—2 of Fig. 1.

The track 1 is here shown as tubular in form, with the longitudinal slot 2 in its lower side. The hanger member 3 is formed with an arm 4 which is bolted or otherwise secured to the outer side of the door and 25 which projects above the same, with a casing 5 at the upper end of said arm which extends inwardly and laterally therefrom and with a hook 6 which depends from the inner side of the casing and is curved toward the arm 4, the length of the said hook being 30 such that the width of the space between its point and the inner face of the arm 4 is less than the outside diameter of the tubular track. A supporting wheel 7, is mounted in the casing on an axle 8, here shown, as a bolt, and the lower side thereof extends below 35 the lower open side of the casing. This wheel 7 is peripherally grooved or channeled to fit the curvature of the track 1, and the said wheel bears and travels on the said tubular track. It will be understood that since the width of the space between the point of 40 the hook and the proximate side of the arm of the hanger member is less than the outside diameter of the tubular track, the hanger member is thereby prevented from being easily disengaged from the track by any vertical or lateral movement of the door.

45 The track is supported by a plurality of brackets suitably spaced apart and secured to the wall; above the doorway of the barn or other structure on which the door hanger is employed. One of these brackets

is shown at 9, and comprises a base portion 10 to be bolted or otherwise secured to the wall, an arm 11 50 which projects outwardly therefrom, an upturned neck 12 at the outer end of said arm, and a head 13, at the upper end of said neck, and here shown as cylindrical in form and of such size as to fit in the bore of the tubular track, the neck extending radially 55 through the slot in the lower side of the tubular track. The neck 12 of the supporting bracket or member is bent or inclined toward the wall parallel or substantially so with the line of stress indicated by the plane b—b of Fig. 2. When the door is in an inclined position such as it assumes when blown outwardly by the force of the wind, said bracket, greatly strengthened by said construction, is enabled to resist the strain exerted thereon caused by the blowing out of 60 the door or other lateral stress to which it may be subjected.

The outward swinging or rocking movement of the door is limited by the terminal of the hook 6 coming in contact with the neck 12 of the bracket 9, and the inward rocking thereof is limited by the inner face 70 of the arm 4 coming in contact with the outer face of the neck 12.

Having thus described my invention, what I claim as new, and desire to secure by Letters-Patent, is,—

1. In a door hanger, the combination of a cylindrical 75 track and a hanger member comprising in its construction an arm extending above the track and on one side thereof, and a hook constructed to extend partially around the opposite side of and under the track and to approach the arm of the hanger to within a distance less than the diameter 80 of the track.

2. In combination with supporting means, and a cylindrical track mounted thereon, of a hanger member comprising an arm having a hook at one end constructed to extend partially around and under said track with the 85 terminal thereof spaced from said arm a distance less than the diameter of the track, and a wheel rotatably supported by said arm in position to engage said track.

3. In combination with a door hanger supporting track and a supporting member for the track having an upwardly extending inwardly inclined neck portion, of a hanger member movably supported on said track and provided with means for engaging said inclined track neck to limit the rocking movement of said hanger on said track.

In testimony whereof I have hereunto set my hand in 95 the presence of two subscribing witnesses.

JOHN H. BURKHOLDER.
